CLAIM

The ornamental design for a bottle, as shown and described.

DESCRIPTION

FIG. 1 is a front, right, and top perspective view of a bottle,
showing our new design;
FIG. 2 is a rear, left, and top perspective view thereof;
FIG. 3 is a front, right, and bottom perspective view thereof;
FIG. 4 is a front elevation view thereof;
FIG. 5 is a rear elevation view thereof;
FIG. 6 is a left side elevation view thereof;
FIG. 7 is a right side elevation view thereof;
FIG. 8 is a top plan view thereof; and,
FIG. 9 is a bottom plan view thereof.

The broken lines adjacent to the shaded areas depict the
boundaries of the claim and form no part thereof. All the
other broken lines in the drawings depict portions of the
bottle that form no part of the claimed design.

1 Claim, 7 Drawing Sheets
